ATTORNEYS.

UNITED STATES PATENT OFFICE.

WILLIAM A. RINGLER, OF PHILADELPHIA, PENNSYLVANIA, ASSIGNOR OF ONE-HALF TO HENRY C. YEISER, OF CINCINNATI, OHIO.

ADJUSTABLE PRICE MARKER.

Application filed September 22, 1922. Serial No. 589,740.

To all whom it may concern:

Be it known that I, WILLIAM A. RINGLER, a citizen of the United States, residing in the city and county of Philadelphia, State of Pennsylvania, have invented a new and useful Adjustable Price Marker, of which the following is a specification.

My present invention comprehends a novel construction and arrangement of adjustable price marker.

It further comprehends a novel construction and arrangement of a frame in the form of an easel, which is constructed in such a manner that it can be supported in a number of ways, such as, for example, by assembling on a file pin, by means of tack, or by the insertion of an ordinary pin, the end of which is bent over, so that the frame can be readily supported at any desired location.

It further comprehends a novel construction of a frame wherein the front face is made of transparent material, preferably of celluloid, provision being made to secure the celluloid to the frame in such a manner that it will not break due to the frequent opening and closing of such transparent front face, a reinforcement being preferable, which is snapped over the juxtaposed edges of the frame.

It further comprehends a novel construction and arrangement of price slips which can be manufactured in single strips with any desired advertising data thereon, and, preferably, having weakened lines in order to facilitate the folding of the strip for visibly indicating the price of the article which is to be sold. By the use of a plurality of strips, any desired combination may be effected.

It further comprehends a novel price strip which is adapted to be printed on both sides with a desired number of numbers in sequence and with any desired advertising matter, so that the strip can be economically printed and the strips can then be cut in desired places in order to form separate strips from which the desired combinations can be made.

It further comprehends a novel construction of a foldable advertising slip which is adapted to be employed in conjunction with the price slips and to be secured in proper position in the frame by folding it so as to cover a portion of the top or bottom or both top and bottom of the price slips.

It further comprehends a novel construction of one or more colored strips which are secured to the frame by means of a transparent cover, so that the advertising matter and the price as well, if desired, may be indicated in color, thereby bringing the purchase price of the article more clearly to the attention of the intending purchaser.

It further comprehends a novel frame of the character described, wherein the frame proper can be formed from a single piece of material bent upon itself and secured together to form an easel, the means for securing the portion of the frame together also serving to secure the body portion of the frame to the transparent cover, which latter is adapted to cover the front face of the frame and to snap or clip over a juxtaposed edge of the frame.

Other novel features of construction will hereinafter more clearly appear in the detailed description and the appended claims.

For the purpose of illustrating my invention, I have shown in the accompanying drawings a typical embodiment thereof which is at present preferred by me, since it will give in practice satisfactory and reliable results. It is to be understood, however, that the various instrumentalities of which my invention consists can be variously arranged and organized and that my invention is not limited to the precise arrangement and organization of these instrumentalities as herein shown and described.

Figure 1 represents a perspective view of an adjustable price marker, embodying my invention.

Figure 2 represents, in rear elevation, the construction seen in Figure 1.

Figure 3 represents a section on line 3—3 of Figure 2.

Figure 4 represents a section on line 4—4 of Figure 2.

Figure 5 represents a section on line 5—5 of Figure 3.

Figure 6 represents, in side elevation, a price marker in assembled condition with respect to a file pin.

Figure 7 represents a rear elevation of the construction seen in Figure 6.

Figure 8 represents, in sectional elevation and in perspective, the adjustable price marker, showing more particularly the manner in which the colored sheets are secured in position.

Figure 9 represents a plan view of one face or strip.

Figure 10 represents a plan view of the opposite face of the strip seen in Figure 9.

5 Figures 11, 12, 13, 14 and 15 represent, respectively, in perspective, different portions of the numbered strip, showing different ways in which they can be folded after they have been cut from the price strip seen in

10 Figures 9 and 10.

Figure 16 represents, in perspective, the strips as folded to indicate a certain sum, and the manner in which the advertising strip is folded to cooperate therewith.

15 Figure 17 represents a section on line 17—17 of Figure 16.

Similar numerals of reference indicate corresponding parts.

Referring to the drawings,

20 1 designates an adjustable price marker embodying my invention which is complete in itself to form as a unit an article of sale.

The adjustable price marker may be considered as consisting of a frame, and the price marker proper, and I will first explain the novel construction and arrangement of frame.

30 The frame.

The frame is preferably formed from a single sheet of sheet material which is bent to form the back or body portion 2, having the outwardly deflected sides 3, which are preferably employed, but which may be omitted if desired.

35 The body portion 2, at its upper end, is downwardly deflected to form the portion 4, which is secured to the body portion by 40 pressing the tongues 5 from the body portion through the back 4 and bending them over, thereby forming clips.

The lower portion of the back 4 forms the easel 6 which is bendable into any desired position, as will be understood by reference to Figures 2, 3 and 6.

45 The easel 6 is provided with one or more apertures 7, so that if it is bent into a horizontal position, as seen in Figure 3, a fastening device 8 may be passed through one of such apertures, or a deflected portion 30 may be used to secure the price marker to its support.

If desired, the easel 6 may be bent or 50 folded, as shown in Figures 6 and 7, so that a supporting pin 9 can be passed through the registering apertures 7, as seen in Figures 6 and 7.

The back 4 is provided with a rearwardly deflected portion 10, thereby forming an aperture 11, see Figure 5, through which can be passed an ordinary pin 12, the upward movement of which will be limited by the head of the pin and the pointed end 65 of the same is then deflected outwardly and

downwardly, so that it forms a hook, which will engage a suitable support, for example, the article itself, or the container for the article which is to be sold.

The front wall of the frame is formed by a transparent strip comprising the back portion 13, which at its upper end, is secured between the body portion and back wall 4 of the marker by means of the same tongues 5 which secure the back wall 4 to the bottom portion 2 of the frame, as will be fully understood by reference to Figures 3 and 4.

70 The rear portion 13 merges into the front wall 14, and, at its upper end, it is rearwardly and downwardly deflected as indicated at 15. In order to prevent the breaking of the edge of the transparent portion due to its repeated engagement and disengagement with the upper edge of the body portion, I prefer to employ a reinforcing strip 16 which is deflected rearwardly and downwardly as at 17 and then upwardly as at 18 in order to receive the flange 15, see 75 more particularly Figure 8.

80 It will now be understood that the price or number indicating strips which are adjustable to make any desired combination, are insertable between the body portion 2 of the frame and its transparent plate 14. 90

85 The price strip.

The construction and arrangement of the price markers is such that, for the purpose of economy, they can be printed on both sides to form a plurality of numbered strips and a strip for the desired advertising matter, which latter preferably indicates the character or quality of the goods which are 100 to be marked.

105 19 designates the price strip as sold to the customer, one side of this strip being shown in Figure 9, and the opposite side being shown in Figure 10.

This strip is provided with perforations 20, so that when separated, it will form the number strips 21, 22, 23 and 24, respectively, and the advertising strip 25. Each of the strips, if desired, may have a weakened line 26 between each number, although this is 115 not necessary because the strips can be readily folded upon themselves without being weakened at such points.

120 The number strip 21 has printed on one face in consecutive order the dollar mark and the numbers 1, 2, 3 and 4. Above each of the numbers 1, 2, 3 and 4, is also indicated the dollar mark. The back of the number strip 21 has indicated thereon in consecutive order the numbers 9, 8, 7, 6 and 125 5, and also in connection with each number is indicated the dollar sign. The number strip 22 has indicated on one face the numbers 0, 1, 2, 3 and 4 and on its opposite face the numbers 9, 8, 7, 6, 5, and on each por- 130

tion of the strip which carries the numbers is also indicated a portion of the name of the corporation, for example, the word "Ringler."

5 The number strips 23 and 24 have the numbers 0, 1, 2, 3, 4, with a line drawn under each number to represent cents or fractions of a dollar and on the reverse face of each of such strips are arranged in consecutive order the numbers 9, 8, 7, 6, 5. Each strip 23 and 24 has indicated on it other matter, such as, for example, the rest of the name of the corporation, for example, as illustrated, the strip 23 above each number 10 has the word "Stores," and above each number on the strip 24 is the abbreviation "Corp."

15 The advertising strip 25 has indicated thereon in spaces the different advertising 20 notations and the directions for the use of the strip.

The operation.

25 When the customer or purchaser desires to use the price marker 19, he separates the strip 19 on the perforated lines 20, thereby forming the separate strips. If, for example, the price to be indicated is \$15.20, the strip 21 is folded, as seen in Figure 11, the strip 22, as seen in Figure 12, the strip 23, as seen in Figure 13, the strip 24, as seen in Figure 14 and the strip 25, as seen in Figure 15.

30 The numerals are now set up in the desired sequence and starting with the strip having the dollar mark.

35 The selected numerals are brought together as seen in Figure 16, so that the price \$15.20 will be indicated, as is apparent.

40 The advertising strip 25 is folded so that the desired matter, such as, for example, "Today only" will cover the bottom of the assembled strips. The assembled matter as seen in Figure 16, is then placed between the guides 3 and against the body portion 2, and the transparent front face 14 is then secured in position by clipping its terminal 45 15 over the upper edge of the body portion.

45 If it is desired to visibly indicate the name of the corporation in color, a color strip of celluloid or other transparent material 26 having an overhanging lip 27 is slid into position between the reinforcing strip 16 and the transparent front face 14, as will be understood by Figure 8, so that the name of the corporation or store will be indicated in color. In a similar manner a color strip 50 may be inserted to cover the advertising matter at the bottom, such as, for example, "Today only," said color strip having a flange, so that it can be slipped into place over the lower portion of the body portion 2.

55 If desired, the displayed matter can be shown in color by placing a color strip 29

over the matter set up as shown in Figure 16, so that the entire price which is being indicated will be shown in any desired color.

60 If a transparent material like celluloid is employed for the front face of the frame to protect the number strips and also to retain them in assembled position, its life is limited if the material has to be bent a number of times at the same place.

65 In my present invention, it will be seen that the transparent strip is secured to the body portion 2 by means of the clips 5, so that when the clip portion 15 is released, the transparent strip simply slides over the body portion 2, so that this bending action does not take place, and the durability and life 70 of the transparent front face of the body portion is much greater than it would be if it was frequently bent at the same place.

75 It will be apparent that in my present invention, the price marker forms in itself a unit, the frame of which serves as a magazine to hold all of the slips which are to be used in connection with it. This eliminates the necessity of having a large number of cards with different numerals and printed matter thereon which necessitates space in storing and a large amount of time in selecting and assembling, whereas in my device the entire matter is self contained and can be readily and quickly changed at the place at which it is to be used to denote any desired descriptive or advertising matter or any desired purchase price within the range of the device.

80 My present invention can be readily adjusted so that it will indicate dollars and cents as may be desired and, as illustrated, any amount from one cent to ninety nine dollars and ninety nine cents can be indicated and by increasing the number of slips a larger amount can be indicated, as will be apparent. The price indicated and the advertising matter is protected by means of the transparent face on the holder so that it does not accumulate dirt and dust, and the price slips can be used indefinitely.

85 Having thus described my invention, what I claim as new and desire to secure by Letters Patent, is:

1. A price marker, comprising a frame having a body portion with forwardly extending flanges at the sides and having a flexible back, a transparent cover secured at one end to said body portion and having means to engage the upper edge of said body portion, and price markers between said transparent cover and body portion.

to engage the upper edge of said body portion, and price markers between said transparent cover and body portion.

3. A price marker, comprising a frame having a body portion with flanges at the sides and having a flexible back, a transparent cover secured at one end to said body portion, a reinforcement for the free end of said cover adapted to engage the juxtaposed portion of said body portion, and price markers between said transparent cover and said body portion.

4. A price marker, comprising a frame having a body portion with flanges forwardly extending at the sides and having a flexible back, a transparent cover secured at one end to said body portion and having means to engage the upper edge of said body portion, and foldable price markers between said transparent cover and body portion.

5. A price marker, comprising a frame having a body portion with flanges at the sides and having a flexible back, a transparent cover secured at one end to said body portion and having means to engage the upper edge of said body portion, price markers between said transparent cover and body portion, and a colored sheet between said cover and said price markers.

6. A price marker, comprising a frame having a body portion with flanges at the sides and having a flexible back, a transparent cover secured at one end to said body portion and having means to engage the upper edge of said body portion, price markers between said transparent cover and body portion, and a foldable advertising strip having one of its folds between said cover and said price markers.

7. A price marker, comprising a frame having a body portion with flanges at the sides and having a flexible back provided with a plurality of pin receiving apertures, a transparent cover secured at one end to said body portion and having means to engage the upper edge of said body portion,

and price markers between said transparent cover and body portion.

8. A price marker, comprising a frame having a body portion, a cover comprising a sheet of celluloid secured at one end at the back of said frame and extending longitudinally to cover the front face of said frame, a reinforcing strip at the free end of said cover adapted to clip over the juxtaposed edge of the frame, and price markers secured in position by said cover.

9. A price marker, comprising a frame having a body portion, a cover comprising a sheet of celluloid secured at one end at the back of said frame and extending longitudinally to cover the front face of said frame, a reinforcing strip at the free end of said cover adapted to clip over the juxtaposed edge of the frame, price markers secured in position by said cover, and a colored transparent sheet between said price markers and cover.

10. An adjustable price marker comprising a frame, a transparent cover for said frame and contributing with it to form a pocket, said cover having one end fixed to said frame and having its opposite end deflected to form a flange to resiliently engage the edge of said frame, and display strips removably placed in the pocket so as to be visible through the transparent cover.

11. An adjustable price marker comprising a frame, a sheet of transparent material extending across the face of the frame so as to form between them a pocket, said sheet having one end secured to said frame and having its opposite end provided with a resilient flange to snap over the edge of the frame and a variable display strip in said pocket and visible through the transparent sheet.

WILLIAM A. RINGLER.
